US0D1054386S

(12) **United States Design Patent** (10) **Patent No.:** **US D1,054,386 S**
(45) **Date of Patent:** **** Dec. 17, 2024**

(54) **CONTACT**

- (71) Applicant: **Samtec, Inc.**, New Albany, IN (US)
(72) Inventors: **Randall E. Musser**, New Albany, IN (US); **Jonathan E. Buck**, New Albany, IN (US)

(**) Term: **15 Years**

(21) Appl. No.: **29/832,053**

(22) Filed: **Mar. 24, 2022**

Related U.S. Application Data

- (63) Continuation of application No. 29/652,012, filed on Nov. 5, 2018, now Pat. No. Des. 950,498.

(57) **CLAIM**

The ornamental design for a contact, as shown and described.

DESCRIPTION

FIG. 1 is a top, front, and left side perspective view of a contact showing our new design;

FIG. 2 is a top, back, and right side perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

1 Claim, 8 Drawing Sheets
